UNITED STATES PATENT OFFICE.

ALFRED W. BURKE, OF WILKINSBURG, PENNSYLVANIA.

LIGHTNING-ARRESTER.

1,107,584.

Specification of Letters Patent. Patented Aug. 18, 1914.

Application filed March 11, 1912. Serial No. 682,883.

To all whom it may concern:

Be it known that I, ALFRED W. BURKE, a subject of the King of Great Britain, residing at Wilkinsburg, in the county of Allegheny and State of Pennsylvania, have invented certain new and useful Improvements in Lightning-Arresters, of which the following is a specification.

This invention is a lightning arrester comprising a loop in series with the line, preferably a triangular spiral, constituting a choke-coil and one arc-horn, and a fixed grounded horn. For use on high-voltage lines, a neutral triangle is interposed between the other two members, providing two arc gaps.

Five types of arresters are shown in the accompanying drawings, in which—

Figure 1 is a perspective view of a two-part arrester, the line member of which consists of a single triangular loop; Figs. 2 and 3 are front and side elevations, respectively, of a two-part arrester the line member of which is a triangular spiral; Figs. 4 and 5 are a front elevation and a plan view, respectively, of a two-part arrester both the line and grounded members of which are triangular spirals; Figs. 6 and 7 are a front elevation and a plan view, respectively, of a three-part arrester having an intermediate neutral triangle; and Fig. 8 is a front elevation of a three-part arrester both the line and grounded members of which are triangular spirals.

The arrester shown in Fig. 1 comprises a line member 1 and a grounded member 2. The line member is a single loop having the form, when viewed from the front, of an equilateral triangle with its apex at the top. One side 3 of this loop constitutes an arc-horn, and the grounded horn-member 2 is supported in arcing proximity thereto. The loop is formed from a round copper rod, bent at its middle to an acute angle 4, to provide straight inclined sides, its terminal portions then being bent inwardly at acute angles 5, 6 to these sides and thence bent outward to provide curved portions 7, 8 lying in a horizontal plane. The ends of the rods are bent into alinement and are rigidly secured in adjacent sockets 9, 10 on the ends of flat copper bars 11, 12, which in turn are secured by cap screws to the upper ends of brass caps 13, 14, held by set screws on the upper ends of insulators 15, 16. The outer

ends of the bars 11, 12 have sockets 17, 18 receiving the line wires 19.

The arrester illustrated in Figs. 2 and 3 is similar to that shown in Fig. 1, except that the line member is a triangular spiral 1', here shown as comprising five concentric turns. This spiral may be bent up from a round copper rod or a flat copper strip, but is usually cast in its final form. The end 8' of the outermost turn extends at right-angles to the plane of the spiral and is bolted to one end 10' of a copper bar 12 receiving the incoming line wire 19. The end 7' of the innermost turn of the spiral is riveted at one end to a copper strip 20, the other end of which is bolted to a copper bar 11' carrying the outgoing line wire 19. In order to rigidly hold the concentric turns of the spiral in equidistant spaced position, they are preferably drilled with several sets of alined holes and a cylindrical fiber rod 21 is driven tightly into each set of holes.

The arrester illustrated in Figs. 4 and 5 is similar to that shown in Figs. 2 and 3, except that the grounded member 2' is a triangular spiral identical with the line member 1'. The end 8' of the outermost turn of the spiral 2' is bolted to one end of a bar screwed to an insulated brass cap, and the end 7' of the innermost turn is grounded.

The arrester illustrated in Figs. 6 and 7 is identical with that shown in Figs. 2 and 3, except that a neutral or electrically-unconnected loop 22 is interposed between the line and grounded members. This loop is a simple triangle bent from a copper rod, with its lower inwardly-turned ends 23 secured in sockets 24 on the ends of a copper bar, screwed to a brass cap 25 on the top of an insulator 26. This insulator is carried by a pin 27, having a circular shank 28 which passes through a hole in the arm 29 carrying the several members of the arrester. The lower end of this shank is threaded and receives a nut 30. By loosening this nut, the triangle 22 can be rotated and set to give any desired arc-gaps between its sides, constituting arc horns, 30, 31, and the opposed horns 3', 2 of the line and grounded members.

The arrester illustrated in Fig. 8 is identical with that shown in Figs. 6 and 7, except that the grounded member 2' is a triangular spiral identical with the line member 1'.

When lightning strikes a line protected by one of these arresters, or when there is any abnormal surge on the line, the loop or spiral member of the arrester acts as a choke-coil or reactance, impeding the flow of current through the loop and causing the current to arc across to the grounded horn. The arc at once climbs the two opposed horns and is thereby broken and extinguished. The current passing around the loop or spiral produces a magnetic field which apparently acts as a blow-out and materially decreases the time required to extinguish the arc. The grounded spiral also acts as a choke-coil or reactance and produces a magnetic field which supplements that set up by the line spiral. The single-loop arrester shown in Fig. 1 can be employed for voltages below fifteen thousand. The two-part arrester with a spiral line-member is effective for voltages up to forty-four thousand. For higher voltages, the three-part arrester having the intermediate neutral triangle is preferably employed.

25 I claim:

1. A lightning arrester, comprising a loop in series with the line, said loop constituting a choke-coil and one of its sides constituting an arc-horn, and a grounded arc-horn in proximity to the line arc-horn.
2. A lightning arrester, comprising a spiral in series with the line, said spiral constituting a choke-coil and one of its sides constituting an arc-horn, and a grounded arc-horn in proximity to the line arc-horn.
3. A lightning arrester, comprising a triangular flat loop in series with the line, said loop constituting a choke-coil and one of its inclined sides constituting an arc-horn, and a grounded arc-horn in proximity to the line arc-horn.
4. A lightning arrester, comprising a triangular spiral in series with the line, said

spiral constituting a choke-coil and one of its inclined sides constituting an arc-horn, 45 and a grounded arc-horn in proximity to the line arc-horn.

5. A lightning arrester, comprising a triangular spiral in series with the line, said spiral constituting a choke-coil and one of its inclined sides constituting an arc-horn, 50 and a grounded triangular spiral arc-horn in proximity to the line arc-horn.

6. A lightning arrester, comprising a loop in series with the line, said loop constituting 55 a choke-coil and one of its sides constituting an arc-horn, a grounded arc-horn in proximity to the line arc-horn, and a neutral member between and having horns opposing said line-horn and grounded-horn. 60

7. A lightning arrester, comprising a loop in series with the line, said loop constituting a choke-coil and one of its sides constituting an arc-horn, a grounded arc-horn in proximity to the line arc-horn, and an adjustable 65 neutral member between and having horns opposing said line-horn and grounded-horn.

8. A lightning arrester, comprising an arc-horn in circuit with the line, and a grounded circuit comprising a choke-coil, 70 one of the sides of said choke-coil constituting an arc-horn, said arc-horns arranged in proximity.

9. A lightning arrester, comprising an arc-horn in circuit with the line, and a 75 grounded triangular spiral, said spiral constituting a choke-coil and one of its inclined sides constituting an arc-horn, said arc-horns arranged in proximity.

In testimony whereof I affix my signature 80 in presence of two witnesses.

ALFRED W. BURKE.
